UNITED STATES PATENT OFFICE.

LUKE EDWARD JENKINS, OF EAST BOSTON, MASSACHUSETTS, ASSIGNOR, BY
MESNE ASSIGNMENTS, TO LOUISA MARIA JENKINS.

FIRE-PROOF CURTAIN.

SPECIFICATION forming part of Letters Patent No. 397,648, dated February 12, 1889.

Application filed January 9, 1888. Serial No. 260,126. (No model.)

To all whom it may concern:

Be it known that I, LUKE EDWARD JENKINS, a citizen of the United States, and a resident of East Boston, in the county of Suffolk and State of Massachusetts, have invented 5 new and useful Improvements in Fire-Proof Curtains, of which the following, taken in connection with the accompanying drawings, is a specification.

10 This invention relates to improvements in fire-proof drop-curtains for theaters, halls, and other similar purposes, and means for raising and lowering such curtains, as will hereinafter be more fully described, reference 15 being had to the accompanying drawings, wherein—

Figure 1 represents a rear elevation of the improved curtain and hoisting device. Fig. 2 represents a plan view of the same. Fig. 3 20 represents a vertical section showing the curtain as lowered, and Fig. 4 represents a similar section showing the curtain raised.

Similar letters refer to similar parts wherever they occur on the different parts of the drawings.

25 *a* is the stage-floor.

b is the proscenium-wall with its opening *b'*, as is usual in theaters or public halls, &c.

c is the curtain, which is made of asbestos 30 cloth, so as to render it perfectly fire-proof, and if so desired it may be wired in the seams to impart additional strength. The upper end of the asbestos curtain is provided with a horizontal pocket, *c'*, in which is loosely introduced an iron or metal pipe, *d*, that is suspended 35 by means of chains *e e e e* from a metal beam, *E*, laid in or forming a portion of the proscenium-wall, as shown. I prefer to use metal chains, as described, for sus-

40 pending the curtain when lowered, instead of wire ropes, so as to prevent liability of kinking, which might occur if wire ropes or wires were used for this purpose. At the lower edge of the curtain *c*, I make likewise a horizontal 45 pocket, *c''*, in which is loosely introduced the metal pipe *d'*, as shown. Between the upper and lower ends of the curtain—say, about two-thirds from the top of the whole height of it—I make another horizontal pocket, *c³*, 50 in which is laid loosely the metal pipe *d''*, as

shown. To said pipe *d''* are attached the hoisting-ropes, hereinafter to be described, by which arrangement the curtain is caused to be looped or folded when raised to its highest position, as shown in Fig. 4, so as to be out 55 of sight from the auditorium when not in use. By the use and employment of an intermediate pipe, *d''*, to which the hoisting-ropes are attached, the curtain can be raised and lowered with a minimum of travel of the 60 hoisting-ropes on account of the curtain being by such means folded or doubled up where said pipe *d''* is located, as shown in Fig. 4.

I wish to state that I do not desire to confine myself to the use of a single pocket, *c³*, 65 and its metal pipe *d''* between the top and bottom edges of the curtain, as two or more may be used, according to the height of such curtain, without departing from the essence 70 of my invention. The object of the aforesaid horizontal pockets *c' c'' c³* and their respective metal pipes *d d' d''* is to allow said pipes to expand freely in case of a fire without interfering with the fire-proof asbestos curtain, thus keeping the latter perfectly smooth, no 75 matter how much the said metal pipes will be expanded by a fire on the stage, and as said pipes are resting loosely in the said pockets they may be heated in case of a fire without any liability of bending or twisting, 80 as might be the case if they were rigidly secured to the curtain.

To the stage-floor, or to the rear of the proscenium-wall, I secure a pair of metal bars or guides, *f f*, one at each side of the proscenium-opening and at a distance back of the proscenium-wall sufficient to permit the lower end of the curtain and its pipe *d'* to pass between such guides and the rear portion of the proscenium-wall, for the purpose 85 of keeping the lower end of the curtain close up to the rear side of the proscenium-wall when the curtain is lowered, and thus cause a close connection between the curtain and the rear portion of the proscenium-wall in 90 case of a fire on the stage, so as to prevent the heat and fire on the stage from reaching the auditorium.

For the purpose of guiding the upper portion of the curtain in its rise and descent, I 100

attach to the rear of the proscenium-wall above the highest point to which the curtain is to be raised a pair of metal wires, $g\ g$ —one on each side of the curtain—which wires pass 5 through the stage-floor and have weights $g'\ g'$ attached to their lower ends for the purpose of keeping them taut; or they may be stretched in any other well-known or equivalent manner. To the sides of the upper portion of the 10 curtain I secure metal rings $g''\ g''$, through which the metal stays or wires $g\ g$ pass loosely for the purpose of holding the curtain in close proximity to the rear of the proscenium-wall when the said curtain is lowered, as shown in 15 Fig. 1.

For the purpose of hoisting and lowering the fire-proof curtain I attach in a suitable manner to the metal pipe d'' the lower ends of the hoisting-ropes $h\ h\ h\ h$, which are carried upward over the pulleys $h'\ h'\ h'\ h'$, and guide-pulleys $h''\ h''\ h''\ h''$ to the drum k of the hoisting apparatus, which latter may be made of any desired construction and operated by hand or steam or other power, as 20 25 30 35 40 45 may be convenient, according to circumstances, said drum being preferably divided by means of rings or flanges $k'\ k'$ in partitions equal to the number of hoisting-ropes, as shown in Fig. 2. The hoisting-drum k has its shaft journaled in bearings in frames $k''\ k''$, as is common in winches, and is provided with a gear-wheel, k^3 , the teeth of which mesh in a pinion secured to the shaft k^4 , provided with a wheel, k^5 , having a crank, k^6 , secured to it, 35 as shown in Figs. 1 and 2. By turning the crank k^6 the drum k is rotated for the purpose of raising the curtain whenever so desired.

To one of the frames k'' of the hoisting 40 45 50 device is pivoted at l' the brake-lever l , provided with a brake-shoe, l'' , which is normally held in frictional contact with the wheel k^5 by means of the weight l^3 , and rope l^4 , one end of which is attached to the lever l and the other end attached to the weight l^3 , as shown in Fig. 1, by which arrangement the hoisting device is locked in position, so as to hold the curtain in its raised position until the rope l^4 is cut or the weight l^3 removed from said rope l^4 , 55 when the curtain is liberated and allowed to descend whenever so required.

The curtain may be instantly lowered by the man in charge of the hoisting apparatus by means of the following mechanism: To the frame k'' is pivoted the releasing-lever m at m' , the rear end of which lever is made to bear against the rear end of the brake-lever l by the depression of the treadle-lever m'' , that is pivoted to the frame k'' or other stationary object, and 55 60 65 is provided with a link or rod, m^3 , connecting it with the forward end of the releasing-lever m , as shown in Fig. 1, and it will thus be seen that if it is desired to instantly lower the curtain this may be done either by removing the weight l^3 , cutting the rope l^4 , or depressing the treadle-lever m'' , as may be found

most convenient. In lowering the curtain it is desirable that it should be accomplished with moderation, so as to prevent its sudden and unchecked descent, and for this purpose 70 I attach to the rear end of the brake-lever l a spring, n , the lower end of which is adjustably secured to the frame of the hoisting apparatus or other stationary object by means of a nut, n' , or equivalent adjustable device, 75 by which arrangement a normal frictional resistance is made to bear against the wheel k^5 , so as to prevent the too sudden descent of the curtain in case the rope l^4 should be cut, the weight l^3 be removed, or the treadle-lever m'' 80 be depressed, as occasion may require. The hoisting-ropes $h\ h\ h\ h$ pass loosely through metal eyes $D\ D\ D\ D$, secured in a suitable manner to the upper pipe, d , as shown in the drawings, and it will thus be seen that when 85 the ropes $h\ h$ are first raised the pipes $d''\ d'$ and the portion of the curtain between them are raised equally with said hoisting-ropes, and the portion of the curtain between the pipe d'' and pipe d is folded, as shown in 90 Fig. 4, until the pipe d'' reaches the upper pipe, d , and the eyes $D\ D$ thereon, when by the continuous upward motion of the ropes $h\ h$ the folded curtain and its pipes $d\ d''\ d'$ are raised sufficiently to cause the lower 95 pipe, d' , and the lower portion of the folded curtain to clear the upper portion of the opening in the proscenium-wall, as shown in Fig. 4, in which position the curtain will be held by the action of the weight l^3 , rope l^4 , 100 brake-lever l , and its friction-shoe l'' , as shown in Fig. 1.

If it is desired to lower the curtain gradually at the close of an act, it is only necessary to depress the treadle-lever m'' , causing the 105 brake-shoe l'' to recede from the wheel k^5 , when the weight of the curtain and its pipes will cause it to gradually descend until the lower pipe, d' , reaches the stage-floor between the guides $f\ f$ and the rear of the proscenium- 110 wall, as shown in Figs. 1 and 3. The same thing may be accomplished by raising the weight l^3 , if so desired.

In case of a fire on the stage the curtain may be lowered by the depression of the 115 treadle-lever m'' by raising the weight l^3 or by removing it from the rope l^4 ; or, in an emergency, by cutting the rope l^4 , in which case the spring n will act on the lever l and its shoe l'' and hold the latter with sufficient pressure 120 against the wheel k^5 to prevent the curtain from falling too quickly, and thus preventing any undue strain on the curtain or its supporting ropes and chains while it is being lowered. With this my improved curtain and 125 mechanism for quickly lowering the same I claim that any fire occurring on the stage can be confined thereto without spreading to the auditorium for a time sufficient for the audience to leave the hall or theater in a quiet 130 and orderly manner, without causing a panic, accidents, or holocaust.

What I wish to secure by Letters Patent and claim is—

1. The fire-proof asbestos curtain *c*, having horizontal upper and lower pockets, *c'* *c''*, and metal pipes *d* *d'*, inserted therein, combined with one or more intermediate horizontal pockets, *c³*, and metal pipe or pipes *d''*, and hoisting-ropes connected to the latter, substantially as and for the purpose set forth.
2. The fire-proof asbestos curtain *c*, having lower horizontal pocket, *c''*, and metal pipe *d'*, one or more intermediate horizontal pockets, *c³*, and pipe or pipes *d''*, hoisting-ropes *h h h*, secured in their lower ends to the said pipe *d''*, and upper horizontal pocket, *c'*, with its pipe *d*, provided with eyes or guides *D D*, through which the hoisting-ropes are passed loosely, substantially as set forth and described.
3. The fire-proof asbestos curtain *c*, having the upper intermediate and lower horizontal pockets, *c'*, *c³*, and *c''*, and corresponding metal pipes *d*, *d''*, and *d'*, arranged in said respective pockets, as described, combined with the hoisting-ropes *h h h h*, guides *D D* on the pipe *d*, and chains *e e*, attached to the upper pipe, *d*, and to the metal beam *E* or other portion of the proscenium-wall, substantially as and for the purpose set forth.
4. The fire-proof curtain *c*, having the horizontal pockets *c'*, *c³*, and *c''*, and the metal pipes *d*, *d''*, and *d'*, placed therein, and having the hoisting-ropes *h h*, arranged and connected for operation as described, in combination with the guide-wires *g g* and rings or ferrules *g'' g''*, secured to the vertical edges of the curtain, substantially as and for the purpose set forth.

5. The fire-proof asbestos curtain *c*, having the horizontal pockets *c'*, *c³*, and *c''*, and corresponding metal pipes *d* *d''* *d'*, supporting-chains *e e*, and hoisting-ropes *h h*, arranged as described, in combination with the hoisting device having the wheel *k⁵*, friction-lever and shoe *l l''*, adjustable spring *n*, releasing-lever *m*, adapted to be actuated by the lever *m''* and the weight *l³* and rope *l⁴*, substantially as and for the purpose set forth.

6. The fire-proof curtain *c*, having the horizontal pockets and metal pipes arranged therein, as described, and having the supporting-chains and hoisting-ropes connected to it, as described, combined with a hoisting apparatus having brake lever and shoe *l l''*, the adjustable spring *n*, and rope *l⁴*, attached to said brake-lever and provided with a weight, *l³*, substantially as and for the purpose set forth.

7. The fire-proof curtain *c*, having the horizontal pockets and metal pipes arranged therein, as described, and having the supporting-chains and hoisting-ropes connected to it, as described, combined with the guides *f f*, for guiding and holding the lower edge of the curtain in close proximity to the rear portion of the proscenium-wall, substantially in a manner as set forth.

In testimony whereof I have signed my name to this specification, in the presence of two subscribing witnesses, on this 3d day of January, A. D. 1888.

LUKE EDWARD JENKINS.
